BULK FLOW CONVEYER

Wilbur G. Hudson, Chicago, Ill., assignor to Gifford-Wood Company, Hudson, N. Y., a corporation of New York

Application December 29, 1945, Serial No. 637,829

1 Claim. (Cl. 198—168)

1

My invention relates to conveyors of the continuous flow type and particularly to conveyors by means of which solid material such as coal, crushed ore, stone, sand, grain, or the like, is carried from one level to a higher level and continuously discharged from the conveyor at said higher level.

Conveyors of this type comprise a casing having up and down vertical runs through which an endless chain, having flights attached thereto travels. The material is introduced into a lower portion of the casing which may be horizontal, and is carried upwardly through the casing by the flights to a discharge point at or near the top of the casing. The flights in such conveyors are sometimes solid or substantially solid, and sometimes open. My invention relates particularly to conveyors having solid or substantially solid flights.

On the vertically upward run of the chain, the flights fit quite closely within the casing and the chain to which the flights are attached passes over a head sprocket positioned somewhat above an opening in the side of the casing through which the material is discharged. While the casing, below the discharge opening, fits quite closely around the flights, above and about this opening the casing is substantially enlarged and is provided with a downwardly sloping bottom, extending around the chain, so that most of the material trapped between the flights while in the smaller section of the casing is laterally released and discharges by gravity as it enters the enlarged portion of the casing above the discharge opening. However, some of the material carried by each flight, depending on the shape of the flight and the angle of repose of the material, is carried upwardly beyond the enlarged portion of the casing and is sometimes carried around the head sprocket and falls down to the lower level from which it must be again raised. In order to facilitate a discharge of the material from the flights when they reach the discharge opening, at the top of the casing, it has been proposed to incline the flights at a substantial angle to the axis of the chain so that the material will slide off the flight by gravity, after the flight has passed out of the vertical run of the casing in which it is closely confined. In order to effect such a sliding off of the material, the flights must be angularly disposed to the horizontal at a rather substantial angle approximating or slightly exceeding the angle of repose of the material conveyed. The effect of so sloping the flights is greatly to increase the friction in the upward vertical run of

2

the conveyor and greatly to increase the wear on that side of the conveyor casing toward which the flights are sloped because the material always tends to slide downwardly on the flights and a wedging of the material occurs between the flights and that side of the casing.

It has also been proposed not only to incline the flights as above described but also to arrange them so that the angle through which they would otherwise ordinarily tilt in passing around the head sprocket is increased and to pass them through a confined opening so that the material remaining thereon is scraped off. Some of the constructions heretofore proposed whereby the normal angle of tilt of the flights is increased, involve the use of multiple head sprockets and complicated chain link and flight constructions and, in most instances, some material is carried around the head sprocket or sprockets because, in sliding from the flights, it slides towards and through the chain instead of away from the chain. Thus, some of the material is caught by portions of the chain and is not discharged.

The principal object of my invention is to provide a simple chain and flight arrangement for a conveyor of this character in which substantially all of the material carried by each flight will be discharged at the top of the upwardly vertical run of the chain and very little, if any, will be carried around the head sprocket. Another object is to provide a chain-flight combination which is of extremely simple construction and in which only single sprockets are necessary. Another object is to provide a chain-flight arrangement in which the material discharged from the flights above the discharge opening is discharged in a direction away from, instead of toward or through, the chain. Another object is to provide a chain-flight arrangement which will accomplish the above objects without increasing the frictional wear on the casing and in which such frictional wear as does occur will be substantially uniformly distributed on all sides of the casing.

With these objects in view, my invention resides in the novel chain-flight combination described below and illustrated in the accompanying drawings in which—

Fig. 1 is a vertical section through a conveyor showing my preferred type of chain;

Fig. 2 is a fragmentary side elevation of the chain;

Fig. 3 is a fragmentary front elevation of the chain;

Fig. 4 is a vertical section through a conveyor

55

3

showing a modified type of chain-flight combination;

Fig. 5 is a fragmentary front elevation of the chain shown in Fig. 4;

Fig. 6 is a fragmentary vertical section of the top of a conveyor having a chain-flight combination similar to that shown in Fig. 1 but in which the chain is reversed;

Fig. 7 is a fragmentary front elevation with portions broken away of the top of a conveyor having a further modified type of chain-flight combination;

Fig. 8 is a fragmentary perspective view of the chain shown in Fig. 7;

Fig. 9 is a fragmentary vertical section, with portions broken away, of a further modified chain and casing;

Fig. 10 is a fragmentary side elevation view of a chain-flight combination differing slightly from that shown in Fig. 9; and

Fig. 11 is a front elevation of the chain shown in Fig. 10.

Referring to the drawings, and particularly to Figs. 1, 2 and 3, the conveyor, as here illustrated, comprises a casing 1 having an upwardly vertical run 2, a downward run 3 and a horizontal run 4. A head sprocket 5 is mounted in the top of the casing and an idler sprocket 6 at the end of the horizontal run. Near the top of the casing, a discharge chute 7 is provided having a downwardly sloping bottom 8 surrounding the chain. Insofar as the casing is concerned, a front elevation view of the top thereof in the vicinity of the discharge chute is the same as shown in Fig. 7. In fact, the discharge chute in each figure is alike irrespective of the type of chain with which it may be associated.

The chains shown in Figs. 1, 2, 3, 5 and 6 are structurally alike and comprise comparatively short links 9, alternating with comparatively long links 11. The links 9 are illustrated as being formed of two flat metal bars in juxtaposed relation but it is to be understood that a single bar instead of two bars may be employed. The flights 10 and the links 11, which are connected to the links 9 by pins 12, are integral and are here shown as formed of bent plates; the flight portions 10 being bent laterally at right angles to the link portions 11. The links 9 are spaced longitudinally of the chain and form, with those portions of the links 11 extending between the links 9, sprocket-tooth-receiving openings 13. Thus, the links 9 ride directly on the sprocket between the teeth while the links 11 straddle the sprocket.

While the openings in the links 9 which receive the connecting pins 12 are adjacent the ends of the links 9, one of the pin-receiving openings in the links 11 is adjacent the front or advance end of the link 11, while the other pin-receiving openings in the links 11 are intermediate the flights 10 and the advance ends of the links 11. Thus, the flights 10 extend laterally outward from rearward extensions of the links 11. The effect of thus arranging the flights is to cause each one to tilt as soon as the forward end of the link 11 to which it is attached, passes the level of the axis of the head sprocket shaft 14.

The chain-flight combination per se, as shown in Figs. 5 and 6, is identical with that described above in connection with Figs. 1, 2, and 3, but the arrangement of the chain with respect to the sprockets, as shown in Fig. 6, is reversed from that shown in Fig. 1. In each case, the flights 10 are disposed at right angles, or perpendicular,

4

to the direction in which the chain travels and the links are at one side of the chain-flight assembly rather than in the center. However, in Fig. 1, the major portions of the flights 10 extend inwardly from the chain as it passes around the head sprocket, while in Fig. 6, the flights extend outwardly from the chain as it passes around the sprockets.

By arranging the chain as disclosed in Fig. 1, two advantages are attained. First, when the flights tilt as shown at the top of Fig. 1, the material thereon slides off in a direction away from the chain, while with the arrangement shown in Fig. 6, the material slides towards the chain. Second, when material to be elevated is charged into the opening 15 and swept off the platform 16 by the movement of the flights, its fall into the bottom of the horizontal run 4 is less obstructed by the chain.

20 In Fig. 9, I have illustrated a fragmentary portion of a preferred type of casing in which the horizontal run of the chain is substantially eliminated and the casing may consist merely of vertically upward and downward runs with a loop boot at the bottom. A charge chute 17 may be provided at the bottom of the loop from which material is discharged into the casing through an opening 18. In this view, the chain links are substantially the same as those shown in Figs. 1, 2 and 3 except in side elevation, the link-forming portions 19 of the flights 20 are substantially rectangular in shape instead of triangular, as shown at 21 in Figs. 1, 2 and 3.

35 In Figs. 10 and 11, I have shown a slight modification of the chain shown in Fig. 9. Here, too, there are long links 31 and short links 32. The long links 31 carry the flights 33 and are the same as the link-forming portions 19 of the chain shown in Fig. 8. However, the flights, instead of being arranged in pairs, as in Figs. 3 and 9 so that each pair fills the casing, half flights are alternately disposed on opposite sides of the chain and fill only about one-half of the cross section 40 of the casing.

45 In Figs. 4, 7 and 8, I have shown a modified form of chain-flight combination. Here, the chain comprises comparatively long links 22 and comparatively short links 23, as in the other two forms of chains illustrated. The advance end of each long link is pivotally connected to the rear end of each short link by means of a pin 24 and the advance end of each short link is connected to the long links 22 by pins 25 at points intermediate the ends of the long links. Sleeves 26

surround the pins 24 and serve not only to maintain the side members of the links in laterally-spaced relation, but also function as rollers which cooperate with the sprocket teeth. In this embodiment, the flights 27 are welded to the rear ends of the long links 22 as shown at 28 and they extend not only laterally of the chain, but also around the outside of the chain as it runs around the sprockets. In other words, the chain, 55 instead of running closely adjacent the side of the casing in the vertical runs thereof, as shown in Figs. 1, 6 and 9, runs in the middle of the casing. However, because the flights are secured to the rear ends of the long links and extend

60 to the rear of the points where these links are articulated with the front ends of the shorter links, the flights begin to swing outwardly and away from the head sprocket and simultaneously tilt, as shown in Fig. 4, as soon as the advance 65 ends of the long links to which they are attached

rise above the level of the axis of the head sprocket.

In operation, the material to be elevated is charged into the conveyor through the opening 15 in Fig. 1, the chute 17 in Fig. 9, or the opening 29 in Fig. 4.

Where a loop boot as shown in Fig. 9, is employed, the charged material falls directly into the bottom of the casing and is carried upwardly by the flights on the chain. Where the casing is of the type shown in Figs. 1 and 4, the charged material is deposited on the platform 16 or 30 and is swept off by the flights returning from the head of the conveyor into the bottom of the conveyor casing where it is carried forwardly and upwardly by the flights. It seems obvious that, where the lower portion of the casing is of the type shown in Fig. 4, the material could be charged through an opening in the side of the casing above the bottom run of the chain.

What I claim is:

A continuous flow conveyor comprising a casing having a vertically-extending section provided with a discharge opening in the side thereof; a single head sprocket only rotatably mounted in said casing above said opening; a continuous chain in said casing comprising comparatively long links disposed in closely spaced, end-to-end relation, and comparatively short links in substantially spaced, end-to-end relation to receive 30

the teeth of said sprocket therebetween; each of said long links comprising straight, longitudinally-extending portions, laterally enclosing the spaces between the ends of adjacent short links 5 and overlying the major portion of the adjacent following short link; said long links having flights integral with the rear ends thereof and extending laterally and horizontally therefrom when in the vertically-extending section of said casing; means 10 pivotally connecting said long links adjacent the front ends thereof to the next adjacent short links adjacent the rear ends thereof; and means pivotally connecting said long links in a zone substantially midway between the ends thereof to the 15 next following short links adjacent the front ends thereof; whereby, as said chain rides up on said head sprocket said flights will be swung away from said sprocket and tilted to discharge the material carried thereby.
